UNITED STATES PATENT OFFICE.

VERNON ROYLE, OF PATERSON, NEW JERSEY.

INSULATING-MACHINE.

SPECIFICATION forming part of Letters Patent No. 678,039, dated July 9, 1901.

Application filed March 15, 1901. Serial No. 51,247. (No model.)

To all whom it may concern:

Be it known that I, VERNON ROYLE, a citizen of the United States, and a resident of Paterson, in the county of Passaic and State 5 of New Jersey, have invented certain new and useful Improvements in Insulating-Machines, of which the following is a specification.

My invention relates to an insulating-machine, with the object in view of providing 10 simple and effective means for preventing the insulating compound from injuriously binding the stock-worm to the central tube, through which the wire to be insulated is conducted to the core and die.

15 In the accompanying drawings, Figure 1 is a view in vertical longitudinal section of so much of an insulating-machine as will suffice to show a practical embodiment of my invention; and Fig. 2 is an enlarged view in detail, partly in section, showing the structure at the joint between the stock-worm and core-bridge.

The general type of machine to which my present invention is directed is that shown, 25 described, and claimed in Letters Patent No. 592,938, granted to me November 2, 1897.

The cylinder within which the stock-worm operates is denoted by *a* and is provided on its interior with a series of annular recesses 30 *b b'*, &c., which become annular chambers when closed along their interior faces by a tubular bushing *c*, which forms a bearing for the stock-worm *d*. The annular chambers *b b'* intercommunicate with one another, and 35 the cooling fluid is admitted to them through a passage-way *e*, which enters opposite an intermediate annular chamber and flows thence into the annular chamber at the rear and thence toward the forward end of the stock- 40 worm, thereby serving to cool the stock-worm throughout its entire length. The stock-worm is keyed to a breech-block *f*, which has a thrust-bearing in a block *g*, as is usual. The core-bridge is denoted by *h* and is held 45 in position by means of a nut *i*, engaged with the supporting-piece *j*, the die *k* being adjustably secured in a supporting-piece *l*, the latter being locked in position by means of a nut *m* and adjusting-screws *n*.

50 My present invention is directed more particularly to the structure of the core-bridge and the parts which coact therewith to form

a tight closure at the joint between the stock-worm and core-bridge to prevent as far as possible the insulating compound from working into position between the stock-worm and central tube, and to further provide in case the material does work to any considerable extent into said position between the stock-worm and central tube, so as to produce a 55 serious binding effect, means whereby this fact may be readily detected before the parts have become seriously impaired.

The core-bridge (denoted, as aforesaid, by *h*) has the rear end of its hub projected, as 60 shown at *o*, within the forward end of the stock-worm, the inner end *p* of said extension *o* being reduced in diameter to form a shoulder *q*, against which the packing gasket or washer *r* abuts to hold the joint. The extension *o p* of the hub is provided with a right screw-thread for the reception of the screw-threaded end *s* of the central tube *t*, through which the wire is led to the core *u* and thence through the die *k*. The tube *t* is 65 provided at its rear end with a thumb-piece *v* for screwing it into the hub. Intermediate 70 of the central tube *t* and the interior of the worm there is a tube *w*, having its forward end thickened, as at *x*, and engaged with the packing *r* and its rear engaged with a tail-screw *y*, having a screw-threaded engagement with the interior of the breech-block *f* and provided with a jam-nut *z* for holding the tail-screw in position. The tube *w* is 75 keyed to the stock-worm to rotate therewith— as, for example, by the well-known feather-and-groove connection—so that it may have at the same time a limited longitudinal movement independent of the worm and central 80 tube for the purpose of forcing the packing *r* against the shoulder *q* on the hub to close the joint tightly between the stock-worm and core-bridge.

In operation when any considerable amount 95 of material works past the packing and into the space between the tube *w* and central tube *t* it will cause the latter to turn, together with the worm, in a direction to unscrew the tube *t* from the hub of the core-bridge, and this being observed by the operator the machine may be stopped, the tube *t* removed, and the interior of the tube *w* cleaned, and, if necessary, the joint between the stock-worm 100

and core-bridge repacked, thus insuring exemption from any material injury or derangement of parts.

If for any cause the worm on the stock-worm should be formed left-handed instead of right, then the screw connection between the tube *t* and the hub of the bridge would be changed to left to correspond, the point being that the connection shall be such between the tube *t* and the core-bridge that the tube *t* shall unscrew when caused to rotate in the direction which the stock-worm rotates to force the insulating compound forward around the core.

15 It is evident that changes might be resorted to in the structure, form, and arrangement of the several parts without departing from the spirit and scope of my invention. Hence I do not wish to limit myself strictly to the structure herein shown and described; but

What I claim is—

1. The combination with the stock-worm and its support, of a core-bridge and its support, the said core-bridge being provided with a hub extension projecting within the forward end of the stock-worm and means for packing the joint between the stock-worm and core-bridge, substantially as set forth.

2. The combination with the stock-worm, core-bridge and their supports, of a central tube having a screw-threaded engagement with the core-bridge, the said screw-threaded connection between the central tube and core-bridge being such that the said central tube

35 will unscrew when rotated in the direction in which the stock-worm rotates to force the stock forward, substantially as set forth.

3. The combination with the stock-worm

and its support, of a core-bridge and its support, the hub of the core-bridge being provided with a right-hand screw-thread within its end adjacent to the stock-worm, a central tube having a screw-threaded engagement with said right-hand screw-thread and means for packing the joint between the stock-worm and core-bridge, substantially as set forth.

4. The combination with the stock-worm, core-bridge and their supports, the core-bridge being provided with a right-hand screw-thread in its hub adjacent to the stock-worm, of a rotary part extending within the stock-worm and engaged with the said right-hand screw-thread for detecting the escape of the insulating compound through the joint between the stock-worm and core-bridge, substantially as set forth.

5. The combination with the stock-worm, and its support, of a core-bridge and its support, the core-bridge being provided with a shouldered hub extension projecting within the stock-worm, a packing engaged with the shouldered projection, a central tube engaged with said projection, a tube intermediate of the stock-worm and central tube and engaged with the packing and means for exerting pressure upon said intermediate tube to adjust the packing, substantially as set forth.

In testimony that I claim the foregoing as my invention I have signed my name, in presence of two witnesses, this 27th day of February, 1901.

VERNON ROYLE.
